ATTORNEY

UNITED STATES PATENT OFFICE.

CHARLES W. MURPHY, OF LOGANSPORT, INDIANA.

INDICATOR FOR MAGAZINES.

1,251,910.

Specification of Letters Patent.

Patented Jan. 1, 1918.

Application filed October 29, 1915. Serial No. 58,665.

To all whom it may concern:

Be it known that I, CHARLES W. MURPHY, a citizen of the United States, residing at Logansport, in the county of Cass and State 5 of Indiana, have invented certain new and useful Improvements in Indicators for Magazines, of which the following is a specification.

An object of my present invention is to 10 provide new and improved means whereby the exact number of shots or loads in the magazine of a pump gun or the like may be readily ascertained without the necessity of removing the magazine tube, which would 15 cause the operator considerable inconvenience; or to facilitate the ascertainment of the correct number of shots or loads that have been fired or used from the original number placed in the magazine.

20 Another object of my invention is to provide such means as is pointed out above which may be constructed in a manner so as to be readily applicable to all of the conventional forms of guns and rifles, and in fact 25 any of the improved forms of weapons wherein the shots or loads are contained in a magazine.

A further object of my invention is to 30 provide a device that is especially designed for use in connection with guns or rifles that are employed for target practice, so as to enable the operator, or the judges, such as the case may be, to accurately ascertain the 35 number of shots or loads fired and the number of loads still remaining in the magazine.

A still further object of my invention is to 40 provide a new and improved device of the type in question that is extremely simple in construction, strong and durable, and highly practical from both the standpoint of the manufacturer and the standpoint of the user; and which, it is believed, may be manufactured at a minimum cost.

45 Various other objects and advantages will become apparent during the continuance of the following description.

These objects are accomplished by such means as are shown in their preferred form in the accompanying drawing, described in 50 the following specification and then more specifically pointed out in the appended claim.

In the accompanying drawings wherein like characters designate like parts throughout the several views;

Figure 1 is a view in side elevation of

repeating rifle, showing my invention, as in its preferred embodiment, in conjunction therewith.

Fig. 2 is a fragmentary view of the rifle 60 barrel showing the magazine in longitudinal section and my invention in conjunction therewith.

Fig. 3 is a view similar to Fig. 2 illustrating my invention in the position it assumes 65 when there are no shots or loads in the magazine.

Fig. 4 is a fragmentary view partly in 70 section of a rifle, illustrating my invention in a slightly modified form.

Fig. 5 is a fragmental side elevation of 75 the modification shown in Fig. 4.

In the drawings A in Figs. 1, 2 and 3 designates a rifle of a conventional type, in connection with which my invention, in the 75 present embodiment, is shown. However it is to be understood that I do not limit myself to that specific form of rifle shown, since my invention, as has been before stated, is readily applicable in connection with approximately all of conventional types of repeating rifles.

The outer magazine tube 10 slidably receives an inner tube 11 that contains the loads or cartridges 12. The outer end of 85 this inner tube 11 is slightly enlarged as at 13 whereby it may be readily turned and moved within the tube 10 when placing the same therein or removing it from the tube 10, and it also carries an upstanding lug 14 90 which may be engaged with a suitable slot in the tube 10 to lock it against removal. A stop 15 is mounted within the tube 11 adjacent its outer end and has one end of the expansive spring 16 bearing thereagainst. 95 The body of the spring 16 projects within a casing 17, that is slidably mounted within the tube 11, while its other end bears against the head 18 of the casing.

In the present embodiment of my invention the tubes 10 and 11 are provided with a series of registering openings 19, the number of openings in each tube being determined by the number of loads that may be accommodated within the magazine. Consequently when the magazine, or rather the tube 11, is filled with the desired number of loads the casing 17 will lie in a position to close a number of the openings corresponding with the number of loads in the magazine. As the loads become used the casing 110 17 will be moved within the tube 11 by ac-

tion of the spring 16 to open successively the openings 19 corresponding with the number of loads used. It will be seen therefore that the operator may at any time refer 5 to the openings 19, should he be in doubt as to the number of loads used or the number of loads remaining in the magazine, to accurately determine the same.

In the embodiment shown in Figs. 4 and 10 5, the openings 19 of the tubes 10 and 11 are eliminated, while each of the said tubes is provided with a slot 20 in place thereof. The slots 20 being in registry to permit a 15 view of the casing 17 and any of the symbols 21 of the casing which may be brought therebefore. It is contemplated to provide the casing 17 with numerals, say from 1 to 8, to correspond with the number of loads contained within the tube 11. Therefore 20 when the tube 11 is filled with the required number of loads a suitable symbol may be viewed through the slots 20 to give indication that the magazine is "full." However as soon as one of the loads is fired the casing 25 will move within the tube 11 to bring the numeral thereon into a position whereby it may be viewed through the slots 20, and so on, as the using of the loads continues.

From the foregoing it is believed that the 30 advantages and novel features of my invention will be readily understood and therefore further detailed description is deemed unnecessary.

Copies of this patent may be obtained for five cents each, by addressing the "Commissioner of Patents, Washington, D. C."

Each of the forms of my invention as shown herein are believed to be equally efficient and it is therefore pointed out that either of these forms may be used if it is so desired. It is also pointed out that I may make certain changes in the construction of my invention and in the arrangement and combination of parts without deviating from the scope thereof, provided of course that such changes fall within the scope of the subjoined claim.

Having thus fully described my invention 45 what I claim as new and desire to secure by Letters Patent is:—

The combination in a gun having a magazine with an opening therein, of a hollow follower having one end closed and its other end open and being slideable in said magazine, and a compression spring having one end extended into the open end of said follower and seated against said closed end and being effective for moving said follower with relation to said opening each time a load is expelled from the magazine, so that different parts of the follower appear through said opening for indicating the 50 number of loads in said magazine.

In testimony whereof I affix my signature in presence of two witnesses.

CHARLES W. MURPHY.
